CATHODE-RAY TUBE

Leonard Albert Woodbridge, Woodford, England,
assignor to A. C. Cossor Limited, London, England, a British company

Application December 21, 1945, Serial No. 636,454
In Great Britain December 28, 1944

5 Claims. (Cl. 250—162)

1

This invention relates to cathode ray tubes. It is well known that fluorescent screens containing sulphides are blackened when bombarded with negative ions, so that their response to electron bombardment is reduced; and various means have been proposed to prevent negative ions which are generated in the cathode region from reaching the target, where they may have this or other deleterious effects.

The phenomenon utilised to this end, both in prior cases and in the present invention, is the difference in responsiveness of electrons and negative ions to the deflecting force of a magnetic field. Thus in some arrangements, the electrodes in the neighbourhood of the cathode are so arranged as to produce a divergent beam of electrons having an axis inclined to the axis of the convergent beam in which the electrons will finally enter the region of variable deflection fields. The beam, preferably before it reaches the intermediate region in which it is converted from divergence to convergence, is passed through a steady magnetic field whereby the electrons are deflected until their axis coincides with the axis of the path along which they will finally enter the region of the variable deflection fields. The negative ions, which are undesired, but are present in the divergent beam entering the steady magnetic field, are not appreciably deflected by this field. They, therefore, strike either an electrode or the side of the tube envelope, and are prevented from reaching the target. Preferably they are so directed as to strike a conducting coating on the side of the neck of the tube envelope or an electrode situated within this neck.

It is an object of the invention, while providing means for preventing ions from reaching the target, to permit the normal design to be retained in which the envelope and the gun electrodes are symmetrical about a common axis, this being a very great convenience in manufacture. The whole envelope of the tube is rotationally symmetrical about the axis of its neck; and the necessary inclination, with respect to that axis, of the beam which issues from the preliminary triode, or equivalent structure, is obtained by asymmetrical placing of the electrodes thereof.

It is a further object of the invention to permit the construction of an electron gun which whilst having a symmetrical arrangement of its electrode discs and other parts about a common axis substantially separates electrons and negative ions in the beam, trapping the ions, and yet provide a resultant electron beam which is paral-

2

lel to or coincident with the said common axis, this object being achieved by the eccentric positioning of the electrode apertures with respect to the said axis and by the application of a single transverse magnetic field.

5 The following description relates to the accompanying drawing which shows a diametral section through the neck of a cathode ray tube embodying the invention.

10 Within the neck 1 of the cathode ray tube is located an electrode-supporting frame consisting of parallel rods 2 and spaced insulating discs 3. Of the three discs shown, the lowermost supports the cathode 4 and grid 5 of the electron gun while the middle and upper support the first anode 6. 15 The cathode 4 is of flat type, with the heating element 7 arranged internally thereof. The grid 5 is in the form of an apertured disc which is dished towards the cathode. The first anode 6 is in the form of a closed cylinder with apertures in its end walls; thus the lower end wall 8 of the cylinder is the anode proper, the peripheral portion 9 constitutes a shield, and the upper end wall 10 is the anode diaphragm.

20 The assembly, as so far described, being symmetrical about the axis 11 of the tube, is well known. In accordance with the present invention, however, the aperture 12 in the grid 5 and the aperture 13 in the anode 8 are each offset 25 from the axis 11—11 in the same radial direction.

25 This offsetting causes the electron beam emerging from the grid aperture 12 to be skewed with respect to, or to cross the desired path which is parallel or preferably coincident with the axis 11.

30 In order to counter-act this skewing, a permanent or electromagnet having a pole M as indicated in the dotted lines in the figure is arranged to develop in the interior of the cylindrical anode 6 a magnetic field of such direction

35 and strength as to cause the electron stream to be restored to parallelism with the axis 11. The path followed by the axis of the electron beam is indicated generally by the dashed line B in the drawing, and it will be seen that this line coincides with the axis 11 as it passes through the aperture 14 in the diaphragm 10. On the other hand, negative ions associated with the stream,

40 not being so substantially affected by the magnetic field, fail to find their way through aperture 14 and tend to be collected on the inner wall of the cylinder, whereby the screen of the cathode ray tube is protected from their effect.

45 The offsetting of the grid aperture 12 in the same direction as the anode aperture 13 should

be such that the apertures overlay in order to permit a beam of electrons to enter cylinder 6. The electron beam, after being skewed by the offset aperture 13 and restored to parallelism by the magnetic field, is preferably brought not only into parallelism with the axis, but coincident with it, so that it emerges from the aperture 14, which is central in the anode diaphragm 10, exactly as it would in the case of a normally-constructed cathode ray tube.

Thus when the grid and first anode apertures are offset in the same direction to the appropriate extents and a restoring magnetic field is applied of an appropriate strength, then the fluorescent screen is not so liable to "burning" as hitherto.

It may be noted as one desirable feature of the construction illustrated that the insulating disc 3 which supports the cathode 4 lies substantially in the same plane as the cathode. In some previous constructions the plane of the supporting disc is below that of the cathode; tilting of the disc out of a plane normal to the axis 11-11 is not liable to affect the amount of offset of the grid aperture appreciably in relation to the cathode or the position of either relatively to the axis.

In an actual embodiment of the invention the dimensions were as follows:

The grid aperture 12 had a diameter .8 mm. and its centre was offset from the axis 11 by a distance of 1 mm. The anode aperture 13 had a diameter 4 mm. and its centre was offset by 2.5 mm. The distance between the two apertures in a direction parallel with the axis 11 was 3.5 mm. The dished portion of grid 5 was 2 mm. in depth.

I claim:

1. A cathode ray tube comprising an evacuated envelope having a neck-portion and a bulbous portion symmetrical about a common axis with a fluorescent screen on the end of the said bulbous portion, an electron gun arranged within said neck portion symmetrically about said axis but having its grid and first anode apertured eccentrically with respect thereto in the same radial direction so that an emergent electron and ion beam is skewed with respect to said axis, and deflecting means acting upon said emergent electron and ion beam to restore the electron portion of the beam to coincidence with the said axis but leaving the ionic portion of the emergent beam relatively undeflected so that the said ionic portion strikes a part of the cathode ray tube other than the said fluorescent screen.

2. A cathode ray tube comprising an evacuated envelope having a neck portion and a bulbous portion symmetrical about a common axis with a fluorescent screen on the end of the said bulbous portion, an electron gun arranged within said neck portion symmetrically about said axis in which the first anode is apertured eccentrically with respect to said axis so that an emergent electron and ion beam is skewed so as

to cross said axis, and deflecting means acting upon said emergent electron and ion beam to restore the electron portion of the beam to parallelism with the said axis but leaving the ionic portion of the emergent beam relatively undeflected so that the said ionic portion strikes a part of the cathode ray tube other than on the said fluorescent screen.

3. A cathode ray tube as claimed in claim 1 in which the electron beam projected from the gun is directed towards a conducting surface within the envelope separate from the said fluorescent screen.

4. An electron gun for cathode ray tubes comprising an anode formed of a closed metallic cylinder, a cathode mounted adjacent one end of said cylinder and on the axis thereof, said end of said cylinder having an aperture formed eccentric to said axis, whereby an electron and ion beam enters said anode cylinder in a direction tending to cross said axis, the other end of said cylinder having a central aperture formed at the axis of the cylinder, and deflecting means acting upon said electron and ion beam within said anode cylinder to deflect the electron portion of said beam and to direct said electron portion out of said central aperture in coincidence with the axis of said anode cylinder.

5. An electron gun for cathode ray tubes comprising, an anode formed of a closed metallic cylinder, a cathode arranged adjacent one end of said cylinder and on the axis thereof, a disk-like grid interposed between said cathode and the adjacent end of said anode, said grid and the adjacent end of said anode having apertures formed therein with their axes eccentric with respect to the axis of said anode and in the same radial direction whereby an electron and ion beam is directed into said anode from said cathode in a direction at an angle to said axis, and deflecting means acting on said beam within said anode for deflecting the electron portion of said beam and directing said portion out of said anode through a central aperture formed in the other end thereof and along a path coincident with the axis of said anode.
